Specification of Letters Patent.

Patented Sept. 1, 1914.

Application filed April 18, 1912. Serial No. 691,721.

To all whom it may concern:

Be it known that I, BURT R. VAN VALKENBURG, citizen of the United States, residing at Oakland, in the county of Alameda and State of California, have invented certain new and useful Improvements in Orchestrions, of which the following is a specification.

This invention relates to musical instruments, and has special reference to an instrument of the player-piano type.

The principal object of this invention is to provide in a musical instrument having a plurality of different tone producing devices, a valve mechanism of improved character for operating one of said devices.

With the above and other objects in view, the invention consists in general of certain novel details of construction, and combinations of parts hereinafter fully described, illustrated in the accompanying drawings, and specifically claimed.

In the accompanying drawings, like characters of reference indicate like parts in the several views, and Figure 1 is a transverse section through a player-piano constructed in accordance with this invention. Fig. 2 is an enlarged detailed section showing a portion of the improved, valve mechanism. Fig. 3 is a detailed plan view partly in the section showing several of the valves and the operating means therefor.

In the present embodiment in the invention there is disclosed a piano case 10 provided with the ordinary action 11. This action 11 may be manually actuated by the keys 12. In order to automatically play the piano, there is provided the usual tracker-board 13, over which extends the roll 14 of perforated paper common to such devices. At 15 is indicated the vacuum chest usual in player-pianos and connected in the usual manner to the tracker-board by a series of tubes, one whereof is indicated at 16. Beneath the vacuum front 15 are the usual bellows 17, which are suitably arranged to raise the prolongs 18 of the piano action. In the upper part of the piano case is located a second musical instrument which is here shown as a xylophone 19, each note whereof is produced by the blow of a hammer 20. Above the xylophone is a vacuum chest 21, on the upper part of which rests a series of bellows, one of which is indicated at 22, and these bellows are connected each to its re-

spective hammer by a rod 23, the hammer being normally held in the raised position by a spring 24. The flow of air from the bellows 22 is controlled by means of a valve 25 and the position of this valve is in turn controlled by a stem 26, resting on a flexible diaphragm 27 which serves to separate the vacuum chest 21 from a cell 28. From the cell 28 leads a passage 29 whereto is connected one end of a tube 30. A bleeder 31 of the usual type is employed to restore equilibrium between the vacuum chest and the cell. Located to the rear of the various prolongs 18 is a valve board 31' provided with a series of openings 32 whereto the remaining ends of the various tubes 30 are connected. On top of the board 31' is hinged a series of valve closures 33. These valve closures project over the forward edge of the board 31' and are arranged to be lifted by a lug 34 carried on the respective prolong so that as the prolong is raised, either mechanically or pneumatically, the respective valve will be opened. Above the board 31' is a strip 35, and the valve closures 33 and strip are provided with opposite disposed recesses 36 wherein are held the respective ends of the springs 37 which serve to turn the closures to an inclosed position. It will be obvious that when one of the valves is open this will act to admit air beneath the respective diaphragm 29 and thus operate the respective hammer 20 in the manner ordinary to devices of this character.

There has thus been provided a simple and efficient device of the kind described, and for the purpose specified.

Having thus described the invention, what is claimed as new is:

An orchestrion including a note sounding device, a tracker board positioned beneath said note sounding device, keys having their inner ends extending beneath said tracker board, a piano action coöperating with said keys and including abstracts extending above the rear ends of said keys whereby said piano action may be operated by said keys, a pneumatic action for said piano action device positioned between said keys and tracker board, and located adjacent said abstracts whereby said pneumatic operator may operate said piano action, a base board positioned to the rear of said abstracts and provided with openings leading to its upper

face, valves pivoted to said base board, and adapted to close the upper ends of said openings and extending over the forward ends of said base board, means carried by 5 said abstracts to operate said valves upon the movement of said abstracts, tubes leading from said note sounding device and communicating with the lower ends of the openings in said base board, and tubes leading

from said pneumatic action to said tracker 10 board.

In testimony whereof I affix my signature in presence of two witnesses.

BURT R. VAN VALKENBURG.
